SOAP DISPENSER

Charles W. Hoppe, Buffalo, N. Y.

Application March 10, 1941, Serial No. 382,491

7 Claims. (CL 221—104)

This invention relates to a soap dispenser and more particularly to a soap dispenser in the form of a unit which can be mounted on a wall or other suitable supporting structure and which is operated by the manual reciprocation of a plunger or push rod thereby to discharge a measured amount of soap.

One of the important objects of the invention is to provide such a soap dispenser which can be refilled with soap in such manner that the soap will not be spilled during the filling operation. For this purpose the container for the soap is adapted to be turned from its inverted operative position to an inoperative position in which the container is upright with its mouth on top and permitting refilling of the container through its mouth.

Another object is to provide such a soap dispenser in which locking means are provided to prevent casual removal of the soap container thereby to prevent persons from loosening or removing the soap container.

Another object is to provide such a soap dispenser in which the wall bracket serves both as a bearing for the turning of the container to position it for refilling and as part of the means for locking the container in either its inverted or upright position.

Another purpose is to provide a powdered soap dispenser in which the powdered soap is agitated adjacent the outlet of the soap container thereby to prevent packing and caking of the soap at this point to insure free and adequate discharge of the powdered soap.

Another aim is to provide a liquid soap dispenser which will not leak, which is positive in operation and which will discharge measured amounts of liquid soap.

Another object is to provide a soap dispenser which is inexpensive to manufacture, which contains a relatively small number of parts, which is positive in functioning and which is not liable to get out of order under conditions of severe and constant use.

Other advantages of the invention will be readily apparent from the following detailed description and accompanying drawings wherein:

Fig. 1 is a vertical central section through a soap dispenser embodying my invention adapted for dispensing powdered soap.

Fig. 2 is a fragmentary vertical section similar to Fig. 1 but showing the operating parts in their discharge position.

Fig. 3 is a fragmentary vertical section taken generally along the line 3—3, Fig. 1.

Fig. 4 is a fragmentary side view, with parts broken away, showing the position of the dispenser for refilling of the soap container.

Fig. 5 is a fragmentary view taken on line 5—5, Fig. 4.

Fig. 6 is a fragmentary top view of the soap dispenser shown in Fig. 1.

Fig. 7 is a horizontal section taken generally on line 7—7, Fig. 1.

Fig. 8 is a vertical central section through a soap dispenser embodying a modified form of my invention adapted for dispensing liquid soap.

Fig. 9 is a fragmentary vertical section similar to Fig. 8 but showing the position of the operating parts during discharge.

Fig. 10 is a fragmentary side view, with parts broken away, showing the position of the liquid soap dispenser for refilling of the soap container.

Fig. 11 is a fragmentary vertical transverse section, taken generally on line 11—11, Fig. 8.

Fig. 12 is a fragmentary enlarged vertical transverse section, taken on line 12—12, Fig. 9.

Fig. 13 is a fragmentary view similar to Figs. 1 and 8 and showing a modified form of means for locking the container to the wall bracket.

In the form of the invention shown in Figs. 1—7, a container 20, preferably of glass, for the powdered soap is shown as mounted on a metal supporting head or holder, indicated generally at 21. The head 21 is shown as being mounted on a wall bracket, indicated generally at 22.

The wall bracket 22 is adapted to be mounted on a wall 23 or other suitable supporting structure. For this purpose a vertically elongated metal anchoring plate 24 is fastened to the wall 23 by a screw 25 which passes through a slot 26 provided in the upper part of this plate as shown in Fig. 1. At its lower end the anchoring plate 24 is shown as being formed to provide a forwardly extending offset, as indicated at 27, and this offset is provided with an opening 28 which provides a bearing surface for a purpose herein-after described. This plate is also shown as being centrally provided with a threaded opening 30.

A wall bracket shell or casing 31 covers the anchoring plate 24 and includes a front panel 32 of any suitable shape and a rim 33, the edge of this rim being adapted to bear against the wall 23. Adjacent its central portion the front panel 32 is provided with an opening 34 which receives a bolt 35. This bolt or screw 35 is recessed into the front panel 32 so that its outer face is flush with the face of the front panel and is screwed into the threaded opening 30 in the

anchoring plate 24. By tightening the bolt 35 it is apparent that the wall bracket shell 31 is drawn into firm engagement with the wall 23.

The supporting head or holder 21 which supports the soap container 20 is swivelly mounted on the wall bracket 22 so as to be capable of turning movement relative to the wall bracket. To this end and as shown in Fig. 1 the head 21 is integrally formed to provide a supporting part 40 which is centrally recessed as indicated at 41 and formed to provide a flat contacting face 42. As best shown in Fig. 5 the flat contacting face 42 is annular in form. A pair of diametrically opposite lugs 43 are integrally formed on the annular face 42 and each of these lugs extends rearwardly from this face toward the wall bracket. Each of these lugs is received in a slot or opening 44 provided in the front panel 32 of the wall bracket shell 31. Between the openings 44 the front panel 32 is formed to provide a forwardly extending frusto-conical part 45 which projects into the recess 41 and the central portion of the part 45 is provided with an opening 46. A pivot rod or shaft 48 is suitably mounted in the supporting head 21 and extends rearwardly, as shown in Fig. 1, through the opening 46 and its free end is rotatably received in the bearing opening 28 in the anchoring plate. The rod 48 carries a cotter pin 49 which acts as a stop pin which is arranged on the front side of the offset 27, a helical compression spring 50 surrounding the rod 48 and being interposed between the pin 49 and the extension part 45. It will therefore be seen that the lower end of the anchoring plate 24 serves as a bearing for the pivot rod 48 and that the spring 50 urges the lugs 43 into locking engagement with the slots or openings 44. With the lugs engaging the slots the head 21 is prevented from turning.

To reduce the cost of the dispenser my invention contemplates the use of a glass container 20 for the soap which container is of a standard design such as is used for containers for food-stuffs. Heretofore the glass containers for dispensers were specifically designed and manufactured and therefore greatly increased the cost of the dispenser unit. I propose to use in my dispenser standard glass jars of the form shown in Fig. 1 which can be purchased in great numbers at low cost. These standard jars are purchased with a metal cover which can also be incorporated in my dispenser unit. In particular the outer end of the neck of the glass jar is integrally formed to provide a male thread 55 which is adapted to receive the threaded flange 56 of the metal cover. The cover has a large central opening 57 of a diameter substantially equal to the inside diameter of the neck. The cover is press fitted into an annular opening or bore 58 provided in the head 21 and the annular edge portion of this cover engages an annular shoulder 59 provided in the head. It will thus be seen that the metal cover with its large opening 57 serves as a threaded engaging surface adapted to secure the glass jar or soap container to the supporting head.

The operative dispensing mechanism is mounted on the head 21 and partially extends into the neck of the soap container 20. This mechanism includes a supporting member 62 in the form of a disk which is supported on an annular shoulder 63 formed in the head 21, this shoulder 63 being formed a slight distance below the shoulder 59. As best shown in Fig. 7 the supporting disk 62 is provided slightly forward

5 of its center with a rectangular opening 64. With this construction the powdered soap 65 in the glass container 20 is prevented from being discharged except through the opening 64 in the supporting disk.

10 Means are provided for measuring out a predetermined amount of powdered soap and discharging the same through an outlet 66 which is provided in the bottom of the supporting head 21. For this purpose a channel shaped guide member 67 is secured to the underside of the supporting disk 62 by a pair of integral retaining fingers 68 on the sides of the guide member each of which fingers extends upwardly through 15 a slot in the supporting disk and is bent laterally on top of this disk, as best shown in Fig. 3. The guide member 67 is open at both ends and preferably does not extend across the full width of the supporting disk. A deflector plate or baffle 69 is struck down from the bottom of the guide member 67 adjacent its rear end to provide a discharge opening and this baffle deflects the charge of powdered soap being expelled from the discharging means toward the outlet 66.

20 A sliding valve member 72 is arranged in the guide member 67 for reciprocable movement therein and an integral push rod 73 extends forwardly from the front side of this valve member out through an opening 74 provided in the side wall of the head 21. A push button 75 is arranged on the outer end of the push rod for facilitating manual reciprocation of the sliding valve member 72. The sliding valve member 72 is provided with a rectangular valve opening 76 of substantially the same dimensions as those of the opening 64 in the supporting disk 62. As best shown in Figs. 1 and 3 the side and front walls forming the opening 76 taper slightly upwardly and outwardly.

25 In order to automatically return the push rod 73 to its extreme outward position spring means are provided which means also carry agitating means to agitate the powdered soap adjacent the opening 64 and thereby prevent the soap from caking or clogging around this opening. For this purpose a substantially U-shaped leaf spring 80 is vertically arranged on the supporting disk 62 in such manner that its free end 81 extends through the opening 64 into the opening 76 in the sliding valve member 72 and is adapted to engage with the front wall of this latter opening, the opposite end 82 of this U-shaped spring being fixed to the upper side of the supporting disk by a securing strap 83 formed in the supporting disk. It will therefore be seen that with the dispensing mechanism in the charging position shown in Fig. 1 the spring 80 urges the sliding valve member 72 to the right as viewed in this figure so that the opening 76 in this valve member is in register with the opening 64 in the supporting disk 62. When the sliding valve member is moved rearwardly or to the left to the discharge position shown in Fig. 2 by pushing on the push button 75 the spring 80 is flexed to the form shown in Fig. 2. Upon release the spring returns the sliding valve member to the right to the position shown in Fig. 1 where it is again in position to receive another charge of powdered soap.

30 The soap agitating means are shown as including a length of wire formed to provide a number of coils 85 arranged transversely of the line of movement of the sliding valve member 72, the opposite ends of this wire being suitably secured to a compacting plate 86 which in turn

is fastened to the U-shaped leaf spring 80 by a securing strap 81 formed in the compacting plate as best shown in Fig. 3. This compacting plate 86 is arranged on that leg of the spring 80 adjacent the forward wall of the opening 76 in the sliding valve member and serves to compact or shove the powdered soap into this valve opening 76 when the sliding valve member is moved to the position shown in Fig. 2. During this movement this compacting plate sweeps across the opening 64 in the supporting disk 62 as best shown in Fig. 3. Also during this movement the wire coils 85 are forced through the powdered soap in the glass container 20 and thereby agitate the soap and free it so that it will flow freely into the valve opening 76. During the return movement of the compacting plate 86 the loosened soap is also urged into the valve opening 76. By providing such agitating and compacting means the discharge of soap is rendered positive and also faster manipulation of the sliding valve member is permitted.

As pointed out above, when the sliding valve member 72 is being loaded or charged its valve opening 76 registers with the opening 64 in the supporting disk 62 and is filled with a measured amount of powdered soap. Upon pushing the valve member to the discharge position shown in Fig. 2 the valve member slides in the guide member 67 and carries its charge of powdered soap into registry with the discharge opening provided by the punched down deflector 69 through which opening the soap drops by gravity onto this deflector which directs the soap out through the outlet opening or mouth 66 into the hand of the user which is held below this mouth.

In order to prevent theft, tinkering with or casual loosening of the glass container 20, locking means are provided which connect the glass container with the wall bracket 22. For this purpose the top of the glass container as shown in Fig. 1 is ground to provide an annular groove 90 into which the edge of a dish shaped metal cap 91 is snapped. To additionally secure the cap 91 to the container the edge of the cap can be glued in the groove 90. The center of this cap is provided with a threaded opening 92 which receives preferably a Parker head screw 93 which carries a collar 94. The collar 94 in its side is provided with a threaded opening 95 which receives the threaded end of a wire lock arm 96. The opposite end of this wire lock arm 96 is screwed into a threaded opening 97 preferably provided in the head of the bolt or screw 35. This wire lock arm 96 closely follows the contour of the container 20 as shown in Fig. 1. With this arrangement when the Parker head screw 93 is screwed into the opening 92 in the cap 91 this cap cannot be pulled off the container. As best shown in Fig. 6 the Parker head screw 93 is provided with crossed slots having tapering bottoms so that an ordinary straight ended screw driver cannot remove such a screw but removal of the screw must be effected by a special screw driver. In this connection the reason for preferring a Parker head screw is to prevent this screw from being loosened or removed by a coin, key or other similar device except by a screw driver particularly designed for Parker head screws. While these locking means are not absolute yet their provision prevents tinkering with and unauthorized loosening of the soap container.

When it is desired to refill the soap container 75

the screw 93 is first removed from engagement with the cap 91 and then the head 21 can be manually grasped and pulled forwardly against the resistance of the spring 50 to remove the lugs 43 from the openings 44 and turned in either direction to the position shown in Fig. 4 where the container is on the underside of the head 21 with the mouth of the container on top and the container can be unscrewed from the threaded insert 56 without danger of spilling the soap. When the container has been refilled it can then be again screwed into the threaded insert 56 and the head returned to the position of the parts shown in Fig. 1.

15 During the turning of the head 21 and container 20 it will be seen that the pivot rod 48 pivots in the opening 28 as a bearing and also that, either in the position of the assembly in Fig. 1 or in Fig. 2, the spring 50 urges the lugs 44 into locking engagement with the openings 43.

20 In the form of the invention shown in Figs. 8-12 the dispenser is shown as being adapted to dispense liquid soap. However, except for a modification of the dispensing mechanism the construction shown in Figs. 8-12 is identical with that shown in Figs. 1-7 and hence the description has not been repeated, the same reference numerals having been applied to indicate identical parts.

25 In the liquid soap dispenser shown in Figs. 8-12, a supporting member 100 in the form of a disk is shown as engaging the shoulder 63, a gasket 101 of rubber or the like being interposed between this supporting disk and the flange of the threaded insert 56. This gasket 101 prevents the liquid soap 102 from leaking around the edge of the supporting disk 100. A tubular cylinder member 103 is arranged underneath the supporting disk and is secured to the same by welding 104 or in any other suitable manner. This cylinder member 103 is closed at its rear end by an integral wall 105 and is open at its opposite or front end, a discharge opening or outlet 106 being centrally provided in the bottom of the cylinder member 40 so that this discharge opening 106 is in line with the outlet mouth 66. As viewed in Fig. 8, to the left of the outlet 106 and in the top of the cylinder member the same is provided with an inlet 107 which places the interior of this cylinder member in communication with the body of liquid soap 102 within the container 20, a nipple connection 108 for this purpose being arranged in an open provided in the supporting disk 100.

45 A piston member 110 is shown as being reciprocably arranged in the bore of the cylinder member 103 and is provided with an axial bore 111 which extends from the rear face of this piston member inwardly of the same a certain distance. A transverse bore 112 intersects the axial bore 111 and places the two in communication with each other, as best shown in Fig. 12. In turn the opposite ends of the transverse bore 112 are in communication with an annular groove 113 provided around the piston member. The piston member extends to a point outside the head 21 through an opening 114 provided in this head and a push button 115 is arranged on the outer end of the piston member. The piston member also carries a stop pin 116 to limit its outward movement and a helical compression spring 117 is interposed between the end face of the piston member and the rear wall 105 of the cylinder member.

50 When the piston member is in the position shown in Fig. 8 liquid soap is permitted to flow

from the container 20 through the inlet opening 107 into the working chamber 118 of the cylinder member 108. When the piston member 116 is manually pushed inwardly against the resistance of the spring 117 to the discharge position shown in Fig. 9 the inner end portion of the piston member closes the inlet opening 107 and starts to compress the liquid soap in the working chamber 118. At this time the annular groove 113 is brought into register with the outlet 106. Upon still further inward movement of the piston member the charge of liquid soap is forced to pass through the communicating passageways or bores 111 and 112 and thereby discharges the liquid soap through the discharge opening 106 which is in line with the outlet mouth 66 of the supporting head 21 into the hand of the user. Upon release of the piston member the spring 117 expands and returns this member to the position shown in Fig. 8 where the working chamber 118 can be refilled or charged again with a measured amount of liquid soap.

The soap container or reservoir 20 in the form of the invention shown in Figs. 8-12 can be refilled in the same manner as with the soap container in the form of the invention shown in Figs. 1-7.

A modified form of locking means connecting the container 20 with the wall bracket 22 to prevent unauthorized removal of the container is shown in Fig. 13 and can be employed with either the form of the invention shown in Figs. 1-7 or with the form illustrated in Figs. 8-12. In Fig. 13 that end of the lock arm 96a connected with the wall bracket is not connected to the head of the screw 35 as illustrated in both forms of the invention in Figs. 1-7 and Figs. 8-12 but is connected to the front panel 32 of the wall bracket shell 31. For this purpose the end of the lock arm is threaded and has brazed thereon a collar 128 which engages with the face of the front panel 32. The threaded end extends through an opening in the front panel and carries a nut 121, a washer 122 being preferably interposed between the nut and the front panel. The opposite end of the lock arm 96a is connected to the container in the same manner illustrated in Figs. 1, 6 and 8.

While I have described the container 20 as being made of glass it is to be understood that any suitable form of container made of any suitable material can be used. It will also be understood that the invention is not limited to the particular forms of construction which have been shown and described for purposes of explanation and illustration but that the construction shown can be varied widely within the scope of the appended claims.

I claim as my invention:

1. In a soap dispenser, having a supporting head, a container adapted to contain a supply of soap removably mounted on said head and manually operable dispensing means arranged in said head for discharging a measured amount of soap, said container being provided with an opening leading to said dispensing means, means for securing said head to a wall comprising a wall bracket, and means for swivelly mounting said head on said wall bracket whereby said head and said container can be turned to an inverted position for removal of said container for refilling the same with soap and including a pivot rod secured to said head and having its outer extremity projecting through an opening provided in said wall bracket, bearing means continuously engaging the said outer extremity of said rod in

said wall bracket and means arranged in a vertical plane disposed between said bearing means and said head for locking said head in an upright operative position.

5. In a soap dispenser adapted to be mounted on a supporting structure and having a supporting head, a container adapted to contain a supply of soap removably mounted on said head and manually operable dispensing means arranged in said head for discharging a measured amount of soap, said container being provided with an opening leading to said dispensing means, means for securing said head to a wall, comprising a wall bracket including an anchoring plate which is provided with a bearing opening, means for mounting said anchoring plate on the supporting structure, a shell encasing said anchoring plate and means for securing said shell to said anchoring plate, a pivot rod secured to said head and journaled in said bearing opening, an interlocking projection and recess provided on said head and said shell and adapted to maintain said head in an upright operative position, and spring means operatively interposed between said pivot rod and said shell for urging said projection and recess into engagement with each other, said head being adapted to be manually moved axially of said pivot rod and against the resistance of said spring means so as to disengage said projection and said recess and permit said head and container to be turned to an inverted position for removal of said container for refilling the same with soap.

3. A soap dispenser adapted to be mounted on a supporting structure, comprising a supporting head, a container adapted to contain a supply of soap mounted on said head, dispensing means arranged in said head for discharging a measured amount of soap, said container being provided with an opening leading to said dispensing means, a wall bracket, means for rotatably mounting said head on said wall bracket, and locking means connecting said container with said wall bracket thereby to prevent casual removal of said container from said head in the normal position of said head.

4. A soap dispenser adapted to be mounted on a supporting structure, comprising a supporting head, a container adapted to contain a supply of soap mounted on said head, dispensing means arranged in said head for discharging a measured amount of soap, said container being provided with an opening leading to said dispensing means, a wall bracket, means for rotatably mounting said head on said wall bracket, and locking means connecting said container with said wall bracket thereby to prevent casual removal of said container from said head in the normal position of said head including a lock arm, means connecting one end of said lock arm to said wall bracket and means for connecting the opposite end of said lock arm to said container.

5. A soap dispenser adapted to be mounted on a supporting structure, comprising a supporting head having a threaded opening, a container adapted to contain a supply of soap and having a threaded neck which is adapted to be screwed into said threaded opening, dispensing means arranged in said head for discharging a measured amount of soap, said container being provided with an opening leading to said dispensing means, a wall bracket, means for rotatably mounting said head on said wall bracket, a lock arm, means connecting one end of said lock arm

to said wall bracket, and means for connecting the opposite end of said lock arm to said container thereby to prevent casual loosening and casual removal of said container from the threaded opening of said head in the normal position of said head.

6. A soap dispenser adapted to be mounted on a supporting structure, comprising a supporting head having a threaded opening, a container adapted to contain a supply of soap and having an open threaded neck which is adapted to be screwed into said threaded opening and also being provided with an annular groove adjacent its end opposite said threaded neck, dispensing means for discharging a measured amount of soap arranged in said head, a wall bracket, means for mounting said head on said wall bracket, a lock arm, means connecting one end of said lock arm to said wall bracket, a collar secured to the opposite end of said lock arm, a screw carried by said collar, a cap arranged on the soap opposite end of said container and engaging said groove, said screw being adapted to be screwed into said cap thereby to prevent casual loosening and casual removal of said container from the threaded opening of said head.

7. A powdered soap dispenser, comprising a supporting head having an outlet, a container for the soap mounted on said supporting head, and means arranged within said head for dis- 30

5 pensing a measured amount of soap through said outlet including a supporting member provided with an opening which is in communication with the body of soap in said container, a guide member carried by said supporting member and provided with a discharge opening, a valve member 10 slidingly arranged in said guide member and provided with a measuring valve opening adapted to contain a measured amount of soap, a leaf spring secured at one end to said supporting member and having its opposite end extending through said opening in said supporting member and into said valve opening, means for agitating the soap adjacent said valve opening including 15 a compacting plate carried by the free end portion of said spring and adapted to move past said opening in said supporting member, an agitator in the form of a plurality of wire coils arranged in the body of soap and carried by said compacting plate, said wire coils being adapted to move in the body of soap and thereby insure the free flow of the powdered soap into the measuring valve opening when the same is being charged, and means for manually sliding said 20 valve member to a discharge position in which said valve opening registers with said discharge opening whereby the measured amount of soap carried by said valve opening drops by gravity through said outlet.

CHARLES W. HOPPE.
